UNITED STATES PATENT OFFICE.

JESSE A. COOK, OF CHICAGO, ILLINOIS.

LIGHTING FIXTURE.

Application filed October 4, 1922. Serial No. 592,223.

To all whom it may concern:

Be it known that I, JESSE A. COOK, a citizen of the United States, residing at Chicago, in the county of Cook and State of Illinois, have invented new and useful Improvements in a Lighting Fixture, of which the following is a specification.

This invention relates generally to supporting devices and more particularly to a device of such nature designed for use as a lighting fixture and intended to support a shade or globe in association with the light producing element.

The general purpose of the invention is the provision of a fixture of the sort indicated which is susceptible of general use by virtue of the fact that it adapts itself to variety in design, manner of support, finish and size, and one which may be manufactured economically, due to its comprising but few parts which may be easily formed and assembled with minimum labor.

A more particular object of the invention is the provision of an article of the sort specified which is adapted to form a secure mounting for shades or globes of glassware or other material designed to be mounted in association with the lamp or light producing source associated with the fixture, and which at the same time will facilitate the mounting and demounting of the globe or shade whenever such may be necessary or desired.

A more particular object is the provision of an improved construction for a fixture having the qualifications above specified, by virtue of which the number of adjustments necessary to accomplish the mounting or demounting of the shade or globe are reduced to a minimum and may be accomplished with one hand, leaving the other hand of the operator free to hold the globe or shade.

More particularly, the object of the invention resides in the provision of a construction for articles of the sort indicated whereby the necessity for globe adjusting or retaining screws is eliminated.

Other and further objects of the invention will be pointed out hereinafter, indicated in the appended claims, or obvious to one skilled in the art, upon an understanding of the present disclosure.

For the purpose of this application I have elected to disclose herein a fixture which is demonstrative of one fashion in which the invention may be embodied, but it is to be understood that the same is here presented

for the purpose of illustration merely, and, consequently, that it is not to be accorded any construction or interpretation which might have the effect of limiting the invention which I purport to secure, short of its true and most comprehensive scope in the art.

In the drawing forming a part of this specification,

Fig. 1 is a side elevation of a fixture with a fragmentary illustration of a globe or shade mounted thereon;

Fig. 2 is a detail in the nature of a part sectional elevation and showing one adjustment of the fixture incident to the mounting or demounting of a globe or shade thereon;

Fig. 3 is a similar detail illustrating the relationship of parts upon the succeeding adjustment; and

Fig. 4 is a detail in the nature of a fragmentary cross section illustrating certain features of the construction.

The nature of the invention will best be understood by reference to these illustrations in detail. By observation of the reference characters applied to the drawing it will be understood that numeral 1 designates a bell or canopy member, which I will term the body member of the fixture, and which member is adapted for association with a lamp support, preferably in such fashion that the latter may be housed and concealed within it. This body member is also adapted for connection to a suitable mounting, as by virtue of the connecting member 2. The body member may be formed conveniently by being spun or stamped out of sheet metal and is formed at one extremity with a member 4, which I will term a globe supporting flange, which preferably extends about the entire perimeter of the body member, constituting in effect an enlargement or flare at the open end thereof. Conjoined to the terminus of this outwardly flaring portion 4, throughout a portion of the peripheral extent thereof, is a globe retaining flange 5, which extends obliquely inward from the globe supporting flange 4 toward the longitudinal axis of the fixture. This globe retaining flange 5 preferably terminates at a rolled bead edge 6 which gives the flange desired strength and rigidity. Formed in the body portion at the other terminus of the flange 4 is a ring retaining member 7 which

may be formed conveniently as an upstanding ledge or shoulder. At a convenient

point on a side of the body portion opposite the retaining flange 5 is mounted the movable globe engaging member 8. This is in the form of a lever which passes through a slot 5 in the portion 7 so that its lower portion is exterior of the supporting flange 4 while this upper portion is within the body member. This lever member is fulcrumed on the body member at the point where it passes through 10 the slot in the latter, and the extremity of its inner arm is movably connected to the body member by means of an arcuate pin 9 fixed in said arm and passing through an aperture in the body member and terminating externally thereof at a head 10. A coiled extension spring 11 is interposed between the head 10 and the outer surface of the body member and has the effect of restraining the outer end of member 8 inwardly toward the 20 axis of the fixture. Said outer end of the adjustable member 8 terminates in an obliquely deflected portion 12 adapted to extend inwardly across the margin of the member 4 toward the longitudinal axis of the device. An adjustable member 14 in the nature of a screw may be mounted on this end portion 12.

Supported on the body member is a movable hood member having a flaring portion 30 15^a conforming generally to the contour of the supporting flange 4, which flaring portion terminates at a skirt portion 15^b and accords a central aperture accommodating the body member. The inner marginal part 35 of the flaring portion 15^a is adapted to rest on top of the shoulder accorded by the abutment member 7 when the edge of the portion 15^a is in closely encompassing association with the body member. Thereby the hood 40 member is held against lateral movement with respect to the body member. Retaining means are provided for holding the hood member against displacement longitudinally of the body member away from the flange 4. 45 This retaining means includes outwardly struck embossments 16 disposed at intervals on the lateral surface of the body member, which embossments are insertable through notches 17 at the inner margin of the hood 50 and adapted to engage over the margin of the hood member when it is rotated to move the notches 17 out of alignment with embossments 16. The hood member is provided with raised embossments 18 disposed in 55 such relationship that one of the embossments 16 may engage between them to retain the hood member against rotation on the body member. When the hood member is thus held on the body member it will 60 envelope the portions 4 and 6 of the latter and will lie above the external arm of the adjustable member 8 in such relationship as to prevent the upward movement thereof. The form and relationship of the globe engaging flange 6 and the member 12 are such

that they will clasp a flaring portion 19^a of a globe or shade 19 inserted between them, whereby to maintain the globe or shade securely affixed to the body member.

In the operation of the device, when it is 70 desired to mount a globe or shade thereon, the hood member is first rotated to a position which will align the notches 17 with the embossment 16, and the side of the hood member over the member 8 is then lifted 75 to a position illustrated in Fig. 2. The adjustable member 8 is then swung by pressure applied to the head 10, which will compress the spring 11 and swing the outer arm of the adjustable member away from the 80 flange 4. This will be effective to further elevate the contiguous portion of the hood member, as illustrated in Fig. 3, and move the portion 12 from in front of the retaining flange 5. The globe then may be 85 inserted and shifted laterally to bring its flaring portion 19^a in contact with the flange 5, whereupon, when pressure is removed from the head 10, the member 12 will be 90 swung inward by the spring 11 into engagement with the flaring neck of the globe. The hood member then being restored to the 95 normal position illustrated in Fig. 1, it will constitute a closed and neat envelopment of the neck of the globe and portions by which it is sustained, giving the fixture an attractive finish and constituting a closure effective to prevent ingress of dust. When retained in this position by the embossments 100 16, as above described, the hood member will form an effective lock which will prevent movement of the adjustable member 8, and thereby prevent inadvertent detachment of the globe. In the operation of the 105 device in the manner just described, either for the mounting of the globe thereon or its demounting, the entire manipulation of the 110 device may be accomplished by one hand, so that the other hand is left entirely free to handle the globe. No adjustment of the 115 screw 14 is necessary in this operation, it being supplied simply for the purpose of permitting variation in the point of contact between the movable retaining member and the globe, so that any variation in the size or form of the latter may be accommodated.

It will be observed that the fixture lends itself to disposal in any position, either pendant, upright or slanting, and forms an 120 effective support for a globe or shade in any position. Other advantages of the device reside in the fact that it affords a very light structure, provides complete concealment of the lamp mounting and prevents ingress of foreign material to the globe, and the 125 spring which is used to control the adjustable member, because of its external disposal, is protected from heat.

I claim:

1. In a fixture, in combination, a body 130

member adapted to support a shade, a shade retaining member on the body member, a lever fulcrumed on the body member and having a portion for engagement with the shade, a spring for swinging the lever to engage the shade, and a hood member forming an envelopment for the lever and the retaining member.

2. In a fixture, in combination, a body member, a stationary globe retaining member mounted thereon, an adjustable globe engaging member mounted on the body member, a spring effective thereon to retain a globe on the retaining member, means supported on the body member for movement to and from position enveloping said retaining and engaging members, and a manipulative means engageable externally of the body member for operating the movable engaging member.

3. In a fixture, in combination, a bell-like body member, a globe retaining member mounted thereon at the open end, a movable globe engaging member mounted on the body member, yielding pressure means holding said engaging member for cooperation with said retaining member, an annular collar movable on the body member to and from a position enveloping the retaining and engaging members and portions of a globe

in engagement therewith, and manipulative means operable externally of the body member for adjusting the engaging member.

4. In a fixture, the combination of a body member, a globe retaining member thereon engageable laterally with a globe, a globe engaging member opposite the retaining member for securing a globe thereon, means for moving the engaging member from in front of the retaining member to permit lateral removal of the globe, and a hood member mounted on the body member to prevent separation of the retaining and engaging members, said hood member being movable to release the engaging member.

5. In a fixture, the combination of a body member, a globe retaining member depending thereon for lateral engagement with a globe, a globe engaging member movably mounted on the body member, yielding pressure means for moving the engaging member to secure a globe on the retaining member, and a hood member for preventing movement of the engaging member against the influence of said pressure means, said hood member being movable to free the engaging member.

In testimony whereof I have hereunto subscribed my name.

JESSE A. COOK.
